United States Patent Office

Des. 190,598
Patented June 13, 1961

190,598

KEY IDENTIFIER

Scipione Roger Manzardo, Wesemlinstrasse 48,
Lucerne, Switzerland

Filed Sept. 10, 1959, Ser. No. 57,497

Term of patent 14 years

(Cl. D50—4)

Fig. 1

Fig. 2

Fig. 3

Fig. 4

Fig. 5

FIG. 1 is a front elevation of a key identifier showing my new design, the key shank shown in broken lines being included for illustrative purposes only;

FIGS. 2 and 3 are side elevations thereof taken from the right and left, respectively of FIG. 1; and

FIGS. 4 and 5 are bottom and top plan views respectively, thereof.

The rear of the key identifier, not shown, is substantially plain.

I claim:

The ornamental design for a key identifier, as shown and described.
